UNITED STATES PATENT OFFICE

161,395

PLATE OR THE LIKE

Rudolph Spreier, Arlington, Va., assignor to Mayer China Company, Beaver Falls, Pa., a corporation of Pennsylvania

Application March 16, 1949, Serial No. 1,424

Term of patent 14 years

(Cl. D44—15)

To all whom it may concern:

Be it known that I, Rudolph Spreier, a citizen of the United States, residing at Arlington, in the county of Arlington and State of Virginia, have invented a new, original, and ornamental Design for a Plate or the like, of which the following is a specification, reference being had to the accompanying drawing, forming part thereof.

In the drawing:

Fig. 1 is a plan view of a plate, showing my new design; and

Fig. 2 is a sectional view taken along a diameter of the plate shown in Fig. 1.

I claim:

The ornamental design for a plate or the like, as shown.

RUDOLPH SPREIER.
